FLEXIBLE DISPENSING BOTTLE FOR CONDIMENTS

Robert W. Morris, New York, N.Y., assignor to Morris Specialties, Inc., West New York, N.J., a corporation of New Jersey

Application May 11, 1959, Serial No. 55,863

Term of patent 14 years

(Cl. D58—8)

Fig:1.

Fig:2.

Figure 1 is a front elevational view of a flexible dispensing bottle for condiments, showing my new design;

I claim:

The ornamental design for a flexible dispensing bottle
for condiments, as shown.
